UNITED STATES PATENT OFFICE

HARRY G. GOULD, OF OSHKOSH, WISCONSIN

DESIGN FOR A ROCKING TOY

Application filed August 24, 1931. Serial No. 40,919. Term of patent 3½ years.

To all whom it may concern:

Be it known that I, HARRY G. GOULD, a citizen of the United States, residing at Oshkosh, in the county of Winnebago and State of Wisconsin, have invented a new, original, and ornamental Design for a Rocking Toy, of which the following is a specification, reference being had to the accompanying drawing, forming part thereof.

The single figure is a side perspective view of a rocking toy showing my design.

The opposite side of the rocking toy bears ornamentation similar to that on the side shown.

I claim:

The ornamental design for a rocking toy, as shown and described.

HARRY G. GOULD.
